JOSEPH WILLIAM PADDOCK, OF PANA, ILLINOIS.

PROTECTIVE CHECK-WRITING ATTACHMENT FOR TYPEWRITERS.

1,332,632.

Specification of Letters Patent.

Patented Mar. 2, 1920.

Application filed January 11, 1919. Serial No. 270,667.

To all whom it may concern:

Be it known that I, JOSEPH W. PADDOCK, a citizen of the United States, residing at Pana, in the county of Christian and State 5 of Illinois, have invented new and useful Protective Check-Writing Attachments for Typewriters, of which the following is a specification.

This invention has reference to protective check writing attachments for typewriters, and its object is to provide means attachable to an ordinary typewriter for movement into and out of operative position, whereby the entire written portion of the 15 check, or so much thereof as may be desired, is protected from alteration by the act of filling in the check.

One form of protecting the check against raising or other changes, is to indent or 20 abrade the written surface so as to disturb or modify the fibers of the paper and thereby prevent changing the surface thus protected, for any changes become at once apparent.

25 The invention contemplates the use of a bar or platen overriding the usual roller platen, the overriding or bar platen being of a character to cause abrasion or other disturbance of the paper surface by the 30 blows imparted thereto by the type of the typewriter, suitable inking means being associated with the extra platen. Such extra platen may be a narrow affair and have a surface of file-like or other appropriate 35 character, and provision is made for the employment of a ribbon which may be forced by the type of the typewriter against the paper, whereby the inking of the paper in conformity with the type and the abrasion 40 or disturbance of the fibers of the paper are simultaneous.

The invention will be best understood from a consideration of the following detailed description taken in connection with 45 the accompanying drawing forming part of this specification, with the understanding, however, that the invention is not confined to any strict conformity with the showing of the drawing, but may be changed and modified so long as such changes and modifications mark no material departure from the salient features of the invention as expressed in the appended claims.

In the drawing:—

55 Figure 1 is an elevation, with some parts

broken away, of a typewriter roller or platen and some associated parts, with the invention applied and in position for writing, the inactive position of the invention being shown in dotted lines.

60 Fig. 2 is a plan view of one end of the structure shown in Fig. 1.

Fig. 3 is a section on the line 3—3 of Fig. 1 with the ordinary typewriter roller or platen shown in dotted lines and distant 65 parts being omitted.

Referring to the drawing, there is shown a typewriter roller or cylinder platen 1 which may be considered as of ordinary construction and therefore requiring no specific description. The roller is provided with a shaft or arbor 2 journaled in upright portions 3 of the main frame of the machine, all these parts being of the ordinary construction and the showing may be taken as indicative of any 70 one of numerous forms of typewriters, it being understood that the invention is applicable to various forms of typewriters with only such changes as slightly different shapes of the typewriter construction 75 may demand. The particular roller platen 1 shown in the drawing is provided at the ends with hubs 4.

80 Freely carried by the hubs 4 are arms 5, 6 respectively, at opposite ends of the roller 85 platen 1, and these arms are of practically the same construction and are joined by a strip or bar 7 having an outer surface 8 of a nature to disturb or abrade the fibers of 90 paper forcibly pressed against it. The surface 8 may be roughened like a file or may be of other abrasive nature, like sandpaper or the surface may be of any nature which will disturb or indent the fibers of the paper in order that typewriter imprints made on the 95 paper may be proof against erasure or change because of such disturbance or abrasion of the fibers.

99 At the same time the disturbance of paper where imprinted is not sufficient to unduly weaken the paper or cause smearing 100 or running of the ink, for the inking and the disturbance of the surface of the paper is caused by the blows of the type upon the paper against an irregular surface of a nature marring such surface to a slight extent 105 but sufficient for the purposes of the invention. The end of the bar 7 where joining the arms 5 and 6 is shouldered to form pockets 9 immediately adjacent to the arms 5 and 6, each pocket being of a size to receive a 110

corresponding end of an inking strip or ribbon 10 held in the respective pockets by clips 11 individual to the pockets. The clips 11 may be made of spring metal so as 5 to be easily inserted into or removed from the pockets and at the same time securely hold the ends of the ribbon 10 in place, leaving the portion of the ribbon between the ends at a sufficient distance from the roughened face 8 of the bar 7 to permit the insertion between the ribbon and the bar of the piece of paper upon which the imprints are to be produced. The piece of paper for 10 which the particular invention is designed, 15 is to be considered as a check, and such check is indicated at 12 in Fig. 3. It will be understood, however, that the paper 12 may represent any piece of paper upon which protective writing is to be produced.

20 In the drawing, the arm 5 is shown as provided with an extension 13 at its outer end constituting a fingerhold or manipulating piece. Of course such fingerhold may be provided on each arm 5 and 6, or but one 25 arm may have such finger-piece

In order that the attachment may be readily applied to or removed from the typewriter, a hinged yoke 14 is provided on each arm 5 and 6, and this yoke terminates in a 30 clip 15 arranged to frictionally engage the respective arm 5 or 6 with the yoke 14 embracing the respective hub 4. The yoke also serves as a pivotal connection permitting the arms 5 and 6 to move about the hub from 35 an approximately horizontal position in the case of a visible typewriting machine, to a position tipped somewhat backwardly and out of the way, whereby the bar 7 may be moved orbitally about the longitudinal axis 40 of the roller platen 1. In order to hold the abrading bar 7 in either the active or the inactive position, there is provided a yieldable strip 16 of sufficient length, with the ends thereof in the path of the manipulating finger-piece 13. The strip 16 carries a 45 clip 17 of elastic nature for application to one end of the frame 3, thus holding the strip 16 in place. At each end the strip 16 has a socket or perforation 18, and the finger-piece 50 or extension 13 is provided with a pin or projection 19 capable of snapping into either one of the sockets 18 to hold the arm and bar 7 in either the active or the inactive position as desired. Thus the strip 16 constitutes a 55 stop for the bar.

It is customary in protecting checks to limit the protection to those portions of the check designating amounts, although the check may be further protected by extending 60 the protection to names as well as amounts. If the protection is to be applied only to the amounts then other parts of the check may be written in on the typewriter, or by hand, as desired, and in either instance 65 the protecting attachment is moved out of

the way, which movement is upward and backward in the particular arrangement shown in the drawing. For writing in the parts to be protected against raising or other changing, the abrading bar 7 is lowered into 70 the path of the type, one of such type being indicated in the raised position at 20 in Fig. 1. If the ribbon 10, which may be provided with indelible ink, is utilized, the usual ribbon of the typewriter is temporarily moved 75 out of the way. The check 12 or other paper to be protected is inserted between the bar 7 and the ribbon 10, and the writing of the amounts, or whatever other writing is to be performed, proceeds in the usual way, with 80 the result that the imprints are made upon the paper by the impact of the type against the ribbon 10, making the imprints upon the paper the same as though the ordinary typewriter ribbon was in place. There is this 85 difference, however, that instead of the blows being received through the paper upon the roller platen 1, they are received upon the roughened surface 8 of the bar 7, which latter may be in sufficiently close relation to 90 the roller platen 1 to be firmly backed up thereby, thus causing the imprints to be sharply and distinctly made. The surface of the paper, where the imprints occur, is 95 ribbed or otherwise disturbed due to the roughened surface against which the type force the paper where striking the latter. The result is that the paper where imprinted is roughened to a sufficient extent to prevent the success of any attempt at change. 100

The attachment simplifies the operation of protecting the check or other paper against change and is always present upon the machine for immediate use or movement out of the way. The protection may be limited or 105 may be extended to all those parts of the check or other paper which are usually filled in, especially those parts capable of being filled in on the typewriter.

It will be understood that the ribbon 10 110 may be next to the roughened bar and the paper passed over it thereby allowing the use of the regular ribbon of the typewriter whereby the letters are inked and impressed on both sides of the paper, or the ribbon 10 115 may be omitted and the regular ribbon only be used.

What is claimed is:—

1. A check protecting attachment for typewriters comprising a bar for interposition in 120 the path of the type, said bar being of a length greater than that of the roller platen of the typewriting machine and provided at the ends with arms for pivotal mounting on the axis of the roller platen, and means for locking the bar in and out of active position, and said bar also being provided with a paper-engaging surface of a roughened character to disturb the fibers of the paper where the latter is struck by the type. 130

2. A check protecting attachment for typewriters, comprising a bar with a paper abrading surface for interposition in the path of the type of the typewriting machine 5 in juxtaposition to but spaced from the platen and extending throughout the length of travel of the platen, said bar being mounted on the axis of the platen for orbital movement about said axis into and out of its type 10 engaging position.

3. A check protecting attachment for typewriters, comprising means having a surface of a character to disturb the fibers of a sheet of paper pressed thereagainst, and supporting means for the first-named means provided with devices for pivotally attaching it to the axis of a typewriter roller platen with the surface of the first-named means in the path of the operated type, said attachment 20 also including inking means in operative relation to the first-named means.

4. A check protecting attachment for typewriters, comprising an elongated bar with terminal arms having means for mounting the bar orbitally with relation to the axis of the roller platen, said bar having a paper-engaging surface of a character to disturb the fibers of the paper, and means for securing inking means to the bar to be 30 located on the face of the paper passing over the bar remote from said bar.

5. A check protecting attachment for typewriters, comprising an elongated bar for location along and closely adjacent to the surface of the typewriter roller platen, said bar having supporting arms at the ends with means for connecting the arms to the axial portions of the roller platen, and a holding bar with means for attaching it 40 to the frame of the typewriting machine, said holding means and the arm portion of the bar having coacting means for holding the bar in either the active or the inactive position.

45 6. A check protecting attachment for typewriters, comprising an elongated bar for location along and closely adjacent to the surface of the typewriter roller platen, said bar having supporting arms at the ends with means for connecting the arms to the axial portions of the roller platen, and a stop with means for attaching it to the frame of the typewriting machine, said stop and the arm portion of the bar having coacting means for holding the bar in either the active or the inactive 55 position, and said bar where attached to the arms having shouldered portions constituting sockets, and clips adapted to the sockets for holding the ends of an inking band or ribbon therein.

60 7. A check protecting attachment for typewriters, comprising a bar with a roughened paper engaging surface and mounted on the ends of the roller platen of the typewriter 65 for orbital movement with respect to the

axis of said roller platen, and an inking ribbon connected at the ends to and carried by said bar for participation in the orbital movement of the bar.

8. A check protecting attachment for typewriters, comprising a bar with a roughened paper engaging surface and mounted on the ends of the roller platen of the typewriter for orbital movement with respect to the axis of said roller platen, and an inking ribbon 75 connected at the ends to and carried by said bar for participation in the orbital movement of the bar, said connections comprising means for attaching the ribbon to and releasing it from the bar at will. 80

9. A check protecting attachment for typewriters, comprising an elongated bar with a roughened paper-engaging face and having terminal arms pivotally mounted on the axis of the typewriter roller platen, coacting locking means on the bar and a fixed portion of the typewriter for locking the bar in either the active or the inactive position, and a manipulating means on the bar for moving the latter from one position to the other. 90

10. A check protecting attachment for typewriters, comprising an elongated bar with a roughened paper-engaging face, means for pivotally supporting the bar on the axial portion of the typewriter roller 95 platen for orbital movement of the bar with relation to said axis, and coacting means on the pivotal supporting means for the bar and on a fixed portion of the frame of the typewriter for holding the bar in either the active or inactive position. 100

11. A check protecting attachment for typewriters, comprising an elongated bar with a roughened paper-engaging face, means for pivotally supporting the bar on the axial portion of the typewriter roller platen for orbital movement of the bar with relation to said axis, and coacting means on the pivotal supporting means for the bar and on a fixed portion of the frame of the typewriter for holding the bar in either the active or inactive position, the holding means on the fixed portion of the typewriter comprising a yieldable strip and a clip of elastic nature for engaging the fixed part of the typewriter with the strip in the path of the holding means on the bar. 110 115

12. A check protecting attachment for typewriters, comprising an elongated bar with a roughened paper-engaging surface, 120 arms at the end of the bar with hinged members for engaging the axial portion of the typewriter roller platen to hold the arms thereto, manipulating means connected to the bar for moving the bar orbitally with relation to the typewriter roller platen into and out of the path of the type, and coacting holding means for the bar connected to the bar and on a fixed portion of the typewriter, including an elastic strip and a clip, whereby 125 130

the bar and the holding means may be attached to or removed from the typewriter at will and without the aid of tools.

13. A check protecting attachment for typewriters, comprising an elongated bar with a roughened paper-engaging surface and pivotally mounted supporting arms at the ends of the bar for attachment to the axial portion of the typewriter roller platen, whereby the bar may be moved into and out of active position with relation to the type, the bar where fast to the arms being shouldered to form pockets, and elastic clips attached to the pockets for holding the ends of an inking ribbon extended over the roughened face of the bar. 15

In testimony, that I claim the foregoing as my own, I have hereto affixed my signature.

JOSEPH WILLIAM PADDOCK.
